UNITED STATES PATENT OFFICE.

GEORGE W. MEYERS, OF RAILWAY, NEW JERSEY, ASSIGNEE TO NATIONAL PNEUMATIC COMPANY, OF NEW YORK, N. Y., A CORPORATION OF WEST VIRGINIA.

DOOR OPERATING ENGINE AND SAFETY SYSTEM.

Application filed May 6, 1923. Serial No. 559,046.

This invention relates to electrically controlled door operating and safety mechanisms which are semi-automatic and operable directly from the power line.

6 A further object includes the provision and arrangement of a simple and efficient door operating and safety mechanism, whereby electrical and mechanical efficiency is maintained at a maximum.

10 Another object embraces the construction of a motor and door operating reduction engine to thereby control a system of doors from a power source in common with the propelling power of the car.

15 A further object includes the construction and arrangement of a safety door control mechanism whereby a door, or group of doors, meeting an obstruction, will automatically reverse the motor and control engine.

20 A still further object includes the provision of mechanism whereby, under certain conditions, the door closing control mechanism will be rendered temporarily ineffective.

25 Other objects will appear hereinafter, and I attain these objects by the mechanism and arrangement of parts illustrated in the accompanying drawing, in which

30 Fig. 1 is a view partly in elevation and partly in section of a control motor and reduction engine;

35 Fig. 2 is a section taken on the lines 2—2 of Fig. 1, through the upper reduction gear and the housing therefor;

40 Fig. 3 is a plan view of the cross-head and base-plate;

45 Fig. 4 is a sectional view, in part, taken on the lines 4—4 of Fig. 1;

50 Fig. 5 is a view showing the door operating mechanism in elevation and mounted on top of the door sill, with doors closed;

Fig. 6 is a plan view thereof with the doors in open position;

55 Fig. 7 is a part of an enlarged plan view showing the doors in closed position;

Fig. 8 is a plan largely diagrammatic showing the several control circuits and safety trip mechanism with push-button control;

Fig. 9 is a view in elevation showing the relays and connections; and

Fig. 10 is an elevation showing the circuit control entrance step.

Similar numerals refer to like parts throughout the several views.

It is among the special purposes of my invention to so construct and arrange my motor and control mechanism as to operate the same directly from the power line in conjunction with the propulsion motors, if desired. For this purpose a number of properly wound motors are mounted in series, and each motor operates its particular set of door operating mechanism in the manner stated above. It is obvious, however, that, if desired, the mechanism may be operated from a suitable storage battery system. Where, for example, the current is taken directly from a power line of a 600 volt system, I mount six shunt wound motors in series to thereby operate as many reduction engines for opening and closing their respective doors or pairs of doors. These doors may be of the folding, or of the sliding type as is desired or made necessary under controlling conditions. Under predetermined conditions, and with aid of proper resistances and relays, my semi-automatic safety mechanism is also operated directly from the same source of power, and the entire mechanism may be put into operation by closing proper circuits by means of the usual push buttons.

Referring now to the drawings, a shunt wound motor 10, of desired voltage, is mounted directly on the upper gear housing 11 of the reduction engine 12. The upper housing of the engine rests directly on a lower housing 13, which in turn rests on a base-plate 14, and these parts are held together by bolts 15 and 16. Within the housings and base-plate of the reduction engine there operate the speed reducing mechanism in the manner described below. From an inspection of Fig. 1, it is evident that the housings serve as a support for the reduction gears and yokes. They further serve also to form a casing for retaining lubricants wherein the said parts float.

Keyed directly to the armature shaft 17, 100 is a drive pinion 18, which meshes with three idler spur gears 19, mounted 120° apart on a planetary reduction yoke 20. The teeth of the idler gears also mesh with an annular gear 21, which may form a part of the outer housing 11, or be secured therein if desired. Yoke 20 is provided with a reduction pinion 22, which, similar to the armature driven

pinion, meshes with a set of three idler gears 23, carried on a second reduction yoke 24, and arranged like those of the first or upper reduction yoke. The gears 23 also mesh 5 with an annular gear 25 in housing 13. To the extension shaft 26 of yoke 24 is fastened a drive plate 27 which has eccentrically secured thereto a drive crank 28, as the drive plate operates back and forth through 180° due to the rotation of the motor in either 10 direction. The drive crank operates to and fro in a slot 29 of the cross-head 30, and thereby causes the cross-head to slide back and forth in the base plate. Grease wells 15 30' maintain lubricant for proper lubrication.

From the description thus far given, it is evident that the rotary motion of the motor may be reduced to any desired degree, depending upon the number and ratio of the 20 reduction gears, and that this motion is finally converted into rectilinear motion which is available, among other uses, for opening and closing doors, for example, on 25 street, subway and railway cars, or the like. To thus obtain converted motion from a high speed motor, it is, of course, understood that the motor is caused to rotate in either direction as may be required by 30 trolling conditions.

As an example of utilizing the reduced and converted motion for opening and closing doors on cars, for example, I have elected to illustrate its application to doors of 35 the folding type. In the specific instance herein illustrated the cross head 30 is provided with extensions 31, at either end, which extensions terminate in link connections 32 for pivotally uniting adjustable connection links 33. These links are connected 40 by means of adjustable clevis 34 to gear segments 35, by any suitable means, as screw bolts 36. The link gear segments 35 co-operate with door moving segments 37, which 45 are securely fastened to the door of door shafts 38 for swinging doors 39 open or shut. Hingedly connected to doors 39 are companion doors 40 having trackers 41 to 50 guide the doors for folding and unfolding when opened and closed, as is well understood.

Directly connected to the link connections of the cross-head and moving therewith, are the cross-head travel limits or circuit breakers 55 42 and 43, for breaking circuits at 44 and 45, respectively, and to thereby limit the rotation of the motor, and likewise the travel of the cross-head and the movements of the doors in corresponding directions. By thus 60 interrupting the respective circuits, relays 46 and 47 drop back to normal for the door opening or door closing movements of motor and cross-head. By closing the circuit, as 65 by a push button 48, relay 47 is energized to close the motor circuit, and the motor is

rotated in the door opening direction, thus causing the operative link connections and associated parts to move from the closed door position as indicated in Figs. 5 and 7 to the open door position as represented in 70 Fig. 6, for example. As the latter position is reached, the corresponding cross-head travel limit interrupts the relay circuit, thus causing the relay to drop back to normal, and stopping the motor by breaking the motor 75 circuit. To close the doors the door closing button 49 is pushed to energize the door closing relay 46, which then closes the motor circuit to rotate the motor in the door closing direction. Under normal conditions the 80 reverse operation now takes place and the doors are quickly and quietly closed.

It frequently happens, however, that conditions arise wherein it is important that the doors be stopped from being closed or even reversed from a closing movement, as where a passenger enters the car, and when he is still in the doorway and is struck by the closing door or doors. To avoid accidents under these or similar conditions, I 90 have provided a system of safety operating and automatic control mechanism, in general, in Fig. 8, in connection with the general plan, and the various electric control 95 circuits and their functions as operated in 100 a push button control. The mechanism which prevents the doors from being closed comprises a circuit opening safety device 50, which is kept in open position by the car step when the step is pressed down, as, for example, by a passenger stepping thereon to enter the car. The weight of the passenger on the step depresses the spring-pressed contact plug carrying contacts 52, and opens the circuit at 105 50 of the current closing button 49 to thereby prevent the guard, or operator, from closing the doors while a passenger enters the car and is still on the step. As soon as the step is free, it 110 will assume the position indicated by the dotted lines, thus permitting the circuit to close in the safety circuit opener 50, and the closing relay 46 can then be energized by closing push button 49.

For opening the door when push button 115 48 is closed, the current travels from the positive side of the power source, through a resistance, the dotted line to magnet 47, contacts 67, push button switch 48 and thence to the negative side of the power 120 source. For closing the door, when push button switch 49 is closed, the current flows from the positive side of the power source, through a resistance, the dotted line to magnet 46, contacts 66, push button 49, circuit device 50, and thence to the negative side of the power source.

If it now happens that a passenger is in the path of the closing doors, and is struck thereby, a tripping mechanism 53 automati- 125 130

cally cuts in the motor reversing relay 54, because the circuit is closed at 64 and 65 and causes the motor to be reversed from the door closing to the opening position. The doors then continue to open until the corresponding cross-head travel limit interrupts the opening circuit and drops the relay back to normal. Since the closing relay is still energized, the door operating engine will automatically reverse and the doors will, in the absence of further obstructions, close in the manner above stated. To prevent the operation from accidentally short circuiting or interrupting the operation of the motor after having been set in motion by energization of the proper relay, I have introduced automatic circuit breakers 66 and 67 which will open the moment when its corresponding relay closes the contacts C, C or O, O. My automatic tripping mechanism comprises a rubber tube 55, extending practically the full length of the inner edges of doors 56 and 57, and the safety relay tripping and circuit closing device 53, which may be carried on the upper edge of the inner doors. The safety tube 55 fits tightly on plug 58 of the circuit closer 53, and terminates in a cup extension 59 having a screw threaded head 60 for the reception of an adjustable contact plug 61. A head 62, integral with plug 58, and having a hole 63 therethrough, slidably carries a pneumatically operated contact cup 64, for closing the circuit through the adjustable contact 65, when the safety tube is compressed, however lightly, as by striking the body of a passenger, or even his hand. The increased pressure thus caused is communicated to cup 64, which is then raised to contact closing position, indicated by the dotted lines, thus closing the relay circuit and energizing relay 54 in the manner outlined above.

While I have designed my construction for 110 volt shunt wound motors in series, it is evident that other units may be employed. In all cases are the fields 70 constantly energized, thereby producing a condition admitting of great flexibility in armature control. As appears further from the diagrammatic outlay of Fig. 8, the operating circuits are separate from the field circuit, and are controlled solely by the push buttons and the automatic control mechanism. Obviously the push buttons may be located at any point on the car or train, or even at a station platform, as may be desired, for operating any number of control circuits and while I have herein illustrated a unit control for one set of doors, it is understood that this device may be applied to each car in a train of cars, which may be operated as stated above, or it may be controlled so as to be operated by individual guards.

It is to be understood that, although I have disclosed and described a specific embodiment of my invention, I do not thereby desire to be understood as having thus limited myself unnecessarily, as various modifications falling wholly within the spirit and scope of my invention will no doubt present themselves to those versed in the art.

What I claim, therefore, as new and useful and of my own invention, and desire to have protected by Letters Patent, is:

1. In a door engine for operating car doors to permit passengers to enter or leave the car, a prime mover mounted to rotate in either direction, means for initiating rotary motion in said prime mover in either direction, means for reducing said rotary motion and converting the same into rectilinear motion to oscillate within predetermined limits, means for automatically confining said movements within said limits to open and close doors, and means controlled by a passenger in a doorway for preventing said doors from closing.
2. In a door engine, a prime mover mounted to rotate in either direction, means for initiating rotary motion in said prime mover in either direction, means rendered effective through abnormal conditions for automatically reversing said motion from one of said moving directions, means for reducing and converting said rotary motion to oscillatory movements, and limiting means for arresting said movements in either direction.
3. In a door engine, a prime mover mounted to rotate in either direction, means for initiating rotary motion in said prime mover in either direction, means rendered effective through abnormal conditions for temporarily reversing said motion from one of said moving directions, means for reducing and converting said rotary motion to oscillatory movements, and means for confining said rotary motion and oscillatory movements within predetermined limits.
4. In a door operating engine, the combination of door shifting mechanism and an electric motor mounted to rotate in either direction for operating said door shifting mechanism, independent electric circuits, one for constantly exciting the field windings of said motor, and the other for energizing its armature under predetermined conditions, and means for limiting the rotation of said armature in either direction and means rendered operative by a passenger in the doorway for affecting said door shifting mechanism.
5. In a door operating engine, the combination of door shifting mechanism and an electric motor mounted to rotate in either direction for operating said door shifting mechanism, independent electric circuits one for constantly exciting the field windings of said motor, and the other for energizing the armature of said motor under predetermined

conditions to either close or open the doors, and means for temporarily reversing the motion of the armature from one of its directions, thereby temporarily preventing the door mechanism from continuing to close the doors.

6. In a door operating engine, the combination of door shifting mechanism and an electric motor mounted to rotate in either direction for operating said door shifting mechanism, a planetary reduction device, and means cooperating with said device to

convert rotary motion into rectilinear motion, independent electric circuits, one for constantly exciting the field windings of said motor, and the other for energizing its armature under predetermined conditions, to either close or open the doors, and means for preventing the door shifting mechanism from becoming operative.

In testimony whereof I have hereunto set my hand on this 4th day of May A. D. 1922.

GEORGE W. MEYERS.
